UNITED STATES PATENT OFFICE

ARTHUR T. BATEMAN AND ANDREW IRVINE, OF DETROIT, MICHIGAN, ASSIGNORS TO
BOHN ALUMINUM & BRASS CORPORATION, OF DETROIT, MICHIGAN, A CORPORA-
TION OF MICHIGAN

MOLDING APPARATUS

Application filed August 17, 1928. Serial No. 300,285.

The invention relates to molding apparatus and refers more particularly to apparatus of the permanent type. One of the objects of the invention is to so construct a permanent mold that it may be quickly and readily operated in forming a casting of complicated shape. Another object is to so construct the mold that the casting may be ejected from the mold cavity. A further object is to so construct the mold that cores may be inserted into and removed from the mold cavity and may be arranged so that they may be readily operated. With these as well as other objects in view, the invention resides in the novel features of construction and combinations and arrangements of parts as more fully hereinafter set forth.

In the drawings:—

Figure 1 is a plan view of the molding apparatus, embodying our invention;

Figure 2 is an enlarged plan view of a portion thereof;

Figures 3 and 4 are cross sections on the lines 3—3 and 4—4 of Figure 1;

Figure 5 is a cross section on the line 5—5 of Figure 3;

Figure 6 is a perspective view of the casting formed in the mold.

The molding apparatus embodying our invention has been designed for use in casting articles of complicated shape, such as valve lifter guides, from metal, such as aluminum or its alloys, having high crystallization shrinkage and low fusing point. The valve lifter guide, as shown in Figure 6 particularly, has the body portion 1 and the transverse tubular portions 2, which extend beyond the opposite sides of the body portion.

These transverse tubular portions have at one end the arcuate extensions 3. The body portion has extending transversely thereof the bosses 4 and the longitudinally extending flanges 5 on the same side as the arcuate extensions. These flanges merge into the tubular portions.

The molding apparatus has the metal base 6 and the pair of permanent mold sections 7 and 8 which are mounted upon the base. Each of these mold sections is movable to-

ward and away from the other and longitudinally of the base and is guided by means of the key 9, which extends longitudinally centrally of the base and is fixedly secured thereto. For moving the sections toward and away from each other, we have provided the yokes 10 and 11 which have their arms fixedly secured to the sides of the sections 7 and 8, respectively, and their bases fixedly secured to the plunger rods 12 adapted to be operated by the air cylinders 13 also mounted upon the base.

The mold sections 7 and 8 have their adjacent faces recessed to form the main mold cavity in which the article is cast. In detail, the mold section 8 is recessed to form that portion of the main mold cavity in which are formed the body portion 1, the bosses 4, the flanges 5 and the parts of the tubular portions 2 with the extensions 3 at the same side of the body portion. The mold section 8 is also provided with the gate 14 extending downwardly from the top and opening into the main mold cavity. The mold section 7 is recessed to form that portion of the main mold cavity in which are formed the parts of the tubular portions 2 at the other side of the body portion 1.

15 are permanent metal cores which extend horizontally and are slidably mounted in the mold section 8 and are adapted to extend through the main mold cavity concentrically of the portions of the recesses for forming the tubular portions 2. These cores are formed with the heads 16 beyond the mold section 8 and providing shoulders engageable by a suitable pry for removing the cores from the main mold cavity. The cores are also provided with the handles 17 principally for use in inserting the cores into 20 the mold cavity.

For the purpose of automatically ejecting the casting formed in the main mold cavity from the mold section 7 upon movement thereof away from the mold section 8, we have provided the ejector rods 18 which extend horizontally above the base 6 and slidably engage at their inner ends the mold section 7. These ejector rods are in alignment with the tubular portions 2 and have 100

the heads 19 at their inner ends for engaging the ends of the tubular portions. The outer ends of these ejector rods are reduced and extend through the bracket 20 which is secured to the base 6 at one end of the key 9. Each ejector rod has sleeved on its reduced end the washer 21 which forms a shoulder engageable with the inner face of the bracket 20 upon movement of the ejector rod with the mold section when the latter is moved away from the other mold section. The annular shoulder 22 upon each ejector rod and formed by reducing the ejector rod and engageable with the washer 21 is so located that the washer contacts with the bracket during the movement of the mold section 7 away from the mold section 8 and before this mold section 7 contacts with the bracket. As a result, the heads of the ejector rods operating upon the ends of the tubular portions 2 cause the casting to be ejected from the mold section 7. For automatically positioning the ejector rods relative to the mold section 7 when the latter is in operative or casting position, this mold section has annular shoulders 23 which are engageable with the heads 19 upon movement of the mold section to casting or operative position. Each ejector rod also preferably has upon its reduced end the nut 24 which is preferably engageable with the outer face of the bracket 20 to serve as a stop for determining the casting or operative position of the mold section 7.

For ejecting the casting formed in the main mold cavity from the mold section 8 upon movement of this mold section from its operative or casting position, we have provided recesses in the mold section 8 forming auxiliary mold cavities at the ends of the main mold cavity and communicating therewith to form ears 25 extending longitudinally beyond the ends of the body portion 1 of the casting. We have also provided the ejector rods 26, which extend horizontally above the base 6 and slidably engage the mold section 8, the inner ends of these ejector rods being engageable with the ears 25 and the outer ends being fixedly secured to the brackets 27 upon the base 6 by suitable means such as the nuts 28 threaded upon the ejector rods and engaging opposite faces of the brackets. With this arrangement the axes of the ejector rods 26 are in the same plane as the axes of the ejector rods 18 and in the median plane of the body portion 1 of the casting so that the casting may more readily be ejected from the mold section 8. Furthermore, no part of the casting formed in the main mold cavity will be damaged. After the casting has been removed, the ears 25 may be severed from the body portion.

For limiting the movement of the mold section 8 from its casting or operative position, there is a stop 29 extending trans-

versely of and fixedly secured to the base 6 and engageable with this mold section.

In operation and with the parts in casting or operative position, the molten metal may be poured through the gate 14 into the main mold cavity and auxiliary mold cavities and after this metal has hardened sufficiently and before the tubular portions 2 have shrunk upon the cores 15, the latter are removed by engaging suitable pries with the heads 16 of these cores. A suitable medium such as air may then be admitted to the cylinders 13, thereby moving the mold sections 7 and 8 from their casting or operative position, during which time the ejector rods 18 and 26 eject the casting from these mold sections, so that it may be readily removed and the parts again placed in casting or operative position.

What we claim as our invention is:

1. In a molding apparatus, the combination with a base, of permanent mold sections arranged on said base and adapted to form a mold cavity, said mold sections including a movable mold section, and means for ejecting the casting formed in the mold cavity of said movable mold section, including an ejector rod slidably engaging said movable mold section, a head upon said rod, a stop upon said base through which the ejector rod slides, means upon said rod and engageable with one side of said stop for limiting the movement of said rod in one direction, means upon said movable mold section and engageable with said head to move said rod in the opposite direction, and means upon said rod engageable with the other side of said stop for limiting movement of said rod by the movable mold section.

2. In a molding apparatus, the combination with a base, permanent mold sections arranged upon said base and movable toward and away from each other and cooperating to form a mold cavity, ejector means secured upon said base at spaced points and adapted to engage respectively the opposite sides of the casting formed in the mold cavity for automatically ejecting the casting from the mold sections upon movement of the sections away from each other, the ejector means engageable with one side of said casting being movable relative to the base upon initial separation of said mold sections.

3. In a molding apparatus, the combination with a base, permanent mold sections arranged upon said base and movable toward and away from each other and cooperating to form a mold cavity, ejector means fixedly secured to said base and arranged to engage one side of the casting, and other ejector means secured to said base and arranged to engage the opposite side of the casting, said last-mentioned ejector means being adapted for limited movement relative to said base.

4. In a molding apparatus, the combina-

tion with relatively movable permanent sections having portions arranged to form the main mold cavity and auxiliary mold cavities in the end thereof, cores associated with the intermediate portion of one of said sections and extending into the main mold cavity, of means for ejecting the casting formed in the mold cavity comprising ejectors associated with said core carrying section adjacent the ends thereof outwardly beyond said cores and arranged to operate upon one side of the casting ears formed in the auxiliary mold cavities, and ejectors arranged to operate upon the opposite side of the casting, one set of said ejectors being mounted for limited movement relative to said base.

In testimony whereof we affix our signatures.

ARTHUR T. BATEMAN.
ANDREW IRVINE.
